JARRING TOOL

Ira J. McCullough, Huntington Park, Calif., assignor to James A. Kammerdiner, Los Angeles, Calif.

Application May 22, 1933, Serial No. 672,164

11 Claims. (Cl. 255—27)

This invention relates to a well tool and relates more particularly to a jarring tool for effecting a jarring action to parts in a well bore. It is a general object of the present invention to provide a simple, practical and particularly effective rotary jar.

The forms of rotary jars or jarring tools that have been introduced, usually involve slackly connected tubular sections that are interposed in the string of drill pipe and that pass or conduct the mud laden circulation fluid flowing downwardly through the string. The impact parts or shoulders of the sections that come into jarring engagement upon actuation of the tool are located within the tubular sections and are of course spaced apart prior to actuation of the tool. The circulation fluid confined in the tubular sections and particularly the fluid trapped between the jarring or impact parts, greatly retards the relative movement of the sections when the tool is actuated, to materially lessen the jarring action and reduce the efficiency of the tool. Attempts have been made to overcome this undesirable feature by providing outlets for the trapped fluid, but the fluid in being very heavy, does not readily flow through the outlets and resists movement between the sections of the tool.

An object of the invention is to provide a rotary jar in which the jarring parts or impact parts are unconfined so that the circulation fluid cannot be trapped between them and interfere with their engagement with one another or retard the relative movement of the sections of the tool.

Another object of the invention is to provide a jarring tool that includes two telescoped and relatively movable sections adapted to jar together, the outer section having a slotted or open wall so that the circulation fluid cannot be trapped within it to retard the relative movement of the sections.

Another object of the invention is to provide a jarring tool in which the means for releasably holding the sections against relative movement are entirely open or exposed so that they cannot become muddled up or rendered inoperative by accumulations of solid matter.

Another object of the invention is to provide a practical and effective jarring tool that is operable to impart both upward and downward jarring impacts to an object in a well.

Another object of the invention is to provide a jarring tool of the character mentioned that may be operated by a simple longitudinal strain

on the operating string, while maintaining a torsional strain on the string.

A further object of the invention is to provide a jarring tool in which lugs or projecting parts on one of the sections cooperate with longitudinal slots in the other section to transmit rotational strains between the sections and thereby provide the jarring effect and form elements of the means for releasably holding the sections against relative longitudinal movement.

A further object of the invention is to provide a jarring tool of the character mentioned that does not in any way interfere with the free flow of circulation fluid through the string.

A further object of the invention is to provide a jarring tool that is easy to control and operate and that is particularly simple and inexpensive of manufacture.

Other objects and features of the invention will be better and fully understood from the following detailed description of a typical form and application of the invention, throughout which description reference is made to the accompanying drawing, in which:

Fig. 1 is a side elevation of the tool provided by the invention illustrating the parts in the latched or unactuated positions. Fig. 2 is a view similar to Fig. 1 illustrating the parts in the actuated positions where the tool has been operated to provide an upward jarring action. Fig. 3 is a longitudinal detailed sectional view of the tool illustrating the parts in the actuated position after the tool has been operated to provide a downward jarring blow. Fig. 4 is an enlarged transverse detailed sectional view taken as indicated by line 4—4 on Fig. 1. Fig. 5 is an enlarged transverse detailed sectional view taken as indicated by line 5—5 on Fig. 2, and Fig. 6 is an enlarged transverse detailed sectional view taken as indicated by line 6—6 on Fig. 3.

The jarring tool provided by the invention, includes, generally, two sections A and B related for limited relative longitudinal movement, means 10 for transmitting rotational strains between the sections A and B and for limiting relative longitudinal movement of the sections, and means 11 associated with the means 10 for releasably holding the sections A and B against relative longitudinal movement.

The body sections A and B of the tool constitute an assembly adapted to be interposed between parts of an operating string or fishing string of drill pipe. In accordance with the invention, the sections A and B are telescoped or

fit one into the other, and are related for relative longitudinal movement. In the drawing I have illustrated the tool connected in a string so that the section A is the upper body section, and the section B is the lower section, it being understood that the tool may be inverted if desired or found practical. The body section A is an elongate tubular member provided at its upper end with means for connecting with the operating string. In the particular embodiment of the invention illustrated, a tapered socket 12 is provided in the upper end of the section A to receive the screw threaded pin 13 of a connecting member or sub 14 in the operating string. The opening 15 of the tubular section A extends longitudinally through the section from one end to the other. The lower body section B extends into the lower end of the opening 15 of the section A and is slideable or operates vertically in the opening. The section B projects from the lower end of the section A and is provided at its lower end with means for connecting with the operating string or a fishing tool, or the like. In the particular construction illustrated in the drawing, a connecting member or sub 16 is threaded on the lower end portion of the section B and is provided at its lower end with a tapered pin 17 threaded into a part 18 on or connected with a fishing tool, or the like.

The means 10 for transmitting rotational strains between the sections A and B and for limiting relative longitudinal movement between the sections includes lugs or projecting parts on one of the sections operating in slots in the other section. In the form of the invention illustrated in the drawing, the means 10 includes lugs or projecting parts 20 on the body section B operating in longitudinal slots 21 in the section A. In accordance with the broader aspects of the invention, there may be any number of cooperating lugs and slots for transmitting torsional strains between the sections A and B and for limiting relative longitudinal movement of the sections. In the form of the invention being described, there are two diametrically opposite lugs or projecting parts 20 on the section B operating in and cooperating with two longitudinal slots 21 in the section A.

The lugs or projecting parts 20 are comparatively heavy and are preferably integral with the body section B. The lugs or projecting parts 20 are provided adjacent the upper end of the section B and are elongate extending longitudinally of the section B. The sides of the lugs or projecting parts 20 are flat and parallel, while the upper and lower ends of the projecting parts are convex or rounded. The lugs or projecting parts 20 may be proportioned so that their outer sides are flush with the periphery of the section A as illustrated throughout the drawing. The slots 21 are provided in the walls of the tubular section A and are shaped and proportioned to slidably pass or receive the projecting parts 20 of the section B. The slots 21 are comparatively long and are provided with flat parallel side walls adapted to slidably cooperate with the sides of the projecting parts 20. In the preferred embodiment of the invention, the upper and lower ends 22 and 23 respectively of the slots 21 are concave and have the same radii of curvature as the ends of the parts 20. The ends of the projecting parts 20 are adapted to engage the ends of the slots 21 to limit relative longitudinal movement of the sections and to provide the jarring action upon the release of the means 11 as will

be subsequently described. It will be apparent how the lugs or parts 20, in cooperating with the side walls of the slots 21 are adapted to transmit torsional or rotational strains between the body sections A and B.

The means 11 for releasably holding the sections A and B against relative longitudinal movement is operable to hold the sections in the latched or unactuated positions illustrated in Fig. 1 of the drawing, and is releasable by a longitudinal strain to cause or allow the sections to suddenly move longitudinally relative to one another to bring the ends of the projecting parts 20 and slots 21 into engagement and provide a jarring action. It is an important feature of the invention that the means 11 may be released by either a heavy tensile strain or a heavy compression strain on the operating string and tool to produce or cause an upward jarring action or a downward jarring action between the sections A and B. The releasable holding means 11 includes series of teeth 27 on the lugs or projecting parts 20 adapted to cooperate with or mesh with series of teeth 28 on the section A. The teeth 27 are formed by a plurality of spaced notches 29 provided in one longitudinal side of each lug or projecting part 20. In the particular embodiment of the invention illustrated in the drawing, the teeth 27 are provided on the rear sides of the parts 20 relative to the forward or clock-wise direction of rotation so that the teeth 27 and 28 may be brought into mesh and held in cooperation by a forward or clock-wise rotational strain on the operating string. The notches 29 in each end of the series of teeth 27 are preferably spaced from the ends of the projecting parts 20 so as to leave continuous or uninterrupted portions 30 at each end of the series of teeth.

The teeth 28 are formed by a plurality of spaced notches 31 in the rear walls of the slots 21. The teeth 29, in being provided on the rear walls of the slots 21 relative to the right hand direction of rotation, face forwardly so as to mesh or cooperate with the rearwardly facing teeth 27 on the parts 20. Comparatively large notches 32 are provided at each end of each series of teeth 27 to receive the uninterrupted portions 30 of the parts 20 and have rounded or concaved walls to receive the rounded ends of the parts 20.

In accordance with the invention, the teeth 27 and 28 are formed so as to cause relative turning between the sections A and B when the sections are put under a heavy longitudinal strain so that the teeth may automatically disengage and permit relative longitudinal movement between the sections A and B and bring the ends of the parts 20 into jarring or hammering engagement with the ends of the slots 21. The upper and lower ends or sides of the teeth 27 and 28 are inclined or converge outwardly toward the outer ends or faces of the teeth. The sides of the teeth 27 and 28 are pitched so as to have sliding engagement when the sections A and B are subjected to a heavy longitudinal strain and thus cause relative turning between the sections A and B in a left hand or counter-clockwise direction. In practice, where the section B is connected with a fishing tool in holding engagement with an object caught in a well bore, the section A is caused to turn in a left hand direction when the tool is subjected to a heavy longitudinal strain so that the teeth 27 and 28 move out of engagement with one another to permit the relative longi-

tudinal movement between the sections which provides the jarring blow. The outer ends of the teeth 27 and 28 may be flat and aligned with the sides of the parts 20 and walls of the slots 21, so that the sections A and B may freely shift longitudinally relative to one another when the teeth are out of mesh and when the teeth 27 and 28 are forced to disengage by a longitudinal strain on the sections A and B, the parts 20 slide longitudinally in the slots 21 until their ends come into jarring engagement with the ends of the slots. The rounded notches 32 at the ends of the series of teeth 28, in having rounded walls, permit the uninterrupted portions 30 at the ends 15 of the parts 20 to readily pass out of them so as to come into sliding contact with the vertical side walls of the slots 21. The uninterrupted portions 30 of the parts 20 prevent premature meshing of the teeth 27 and 28 when the tool is being set or latched and prevent the teeth from chattering or ratcheting together when they have been released. In the form of the invention disclosed in the drawing, the inner walls 35 and 36 of the notches 29 and 31 are pitched relative to 20 the central longitudinal axis of the tool so that the teeth 27 and 28 are wider at their outer ends than they are at their inner ends. It will be apparent how the means 11 may be latched by bringing the teeth 27 and 28 into meshing engagement, and how the means 11 may be released by putting a heavy longitudinal strain on the tool to cause the pitched sides of the teeth to slide out of engagement to force the section A to turn relative to the section B so that the 25 ends of the parts 20 may come into jarring engagement with the ends of the slots 21. Whether an upward or downward jarring action is produced of course depends upon whether a tensile or compression strain is placed upon the tool to release the means 11. An extremely heavy jarring action may be brought about by maintaining a right hand torsional strain on the section A while releasing the means 11 so that a heavier longitudinal strain is required to cause the disengagement of the meshing teeth 27 and 28.

The invention provides means for conducting the circulation fluid through the sections A and B. A central longitudinal fluid passage 40 is provided in the section B and extends from the lower end of the section to the upper end of the section where it communicates with a wash pipe 41. The wash pipe 41 projects upwardly from the upper end of the section B and extends upwardly through the upper portion of the section A and may project into the sub 16. Means is provided to seal or pack about the wash pipe 41. In the particular case illustrated in the drawing, the packing or sealing means consists of a restricted portion 42 to the opening 15 having a plurality of longitudinally spaced annular grooves 43. The wash pipe 41 is slideable longitudinally in the restricted portion 42 of the opening 15, and liquid in the grooves 43 forms a liquid seal about the wash pipe. Circulation fluid is conducted downwardly through the wash pipe 41, the passage 40, and flows through the passage 44 of the sub 16 to the fishing tool, or lower end portion of the string.

It is believed that the operation of the jarring tool provided by the present invention will be readily understood from the foregoing detailed description. In order to latch the means 11 or bring the teeth 27 and 28 into meshing engagement, the sections A and B are shifted relative to one another to bring the teeth 27 and 28 in alignment and the section A is turned in a right hand

direction to cause the teeth to come into meshing cooperation. The continuous or uninterrupted portions 30 at the ends of the series of teeth 31 prevent partial or premature engagement of the teeth 27 and 28, and prevent chattering or jarring together of the teeth as the means 11 is set or latched. If it is desired to operate the tool to produce an upward jarring action, a right hand torsional strain and a heavy upward or tensile strain is put on the operating string and tool. The torsional strain is maintained on the string during the operation of the tool. The teeth 27 and 28 cooperate to transmit this longitudinal strain between the sections A and B, and are not caused to disengage until a very heavy tensile strain is put on the operating string which will stretch or extend the string to a great extent. When a sufficiently heavy tensile strain is put on the operating string, the pitched or inclined ends of the meshing teeth 27 or 28 cause the upper section A to turn in a left hand direction relative to the section B against the torsional strain maintained on the string so that the teeth snap out of engagement and allow the section A to move upwardly relative to the section B so that the lower ends 23 of the slots 21 come into jarring engagement with the lower ends of the parts 20. Upon the release of the means 11, the stretched or extended operating string is suddenly permitted to contract and this contracting of the string is utilized to effect the jarring action. It will be apparent that while a torsional strain is maintained on the string, an extremely heavy tensile strain must be put on the tool to cause the engaging teeth 27 and 28 to force the section A to turn in a left hand direction relative to the section B so that they are released to permit the upward movement of the section A relative to the section B and bring about the upward jarring action. The intensity of the jarring blow produced is dependent upon the torsional strain maintained on the tool for when a comparatively heavy right hand torsional strain is maintained on the tool a very heavy tensile strain is required to release the tool. The tool may be operated to produce a succession of heavy upward jarring blows by alternately subjecting the operating string to a heavy tensile strain and allowing it to settle or lower so as to successively release and engage the latching teeth 27 and 28.

To provide a downward blow or jarring impact to the object in the well, the teeth 27 and 28 are first brought into meshing engagement by putting a right hand torsional strain on the operating string and manipulating the string to bring the teeth into engagement, and the operating string is permitted to settle or lower so that the sections A and B are put under a heavy compression strain. The torsional strain is maintained on the string, and when this compression strain becomes sufficiently heavy, the pitched or inclined sides of the teeth 27 and 28 cause the section A to turn in a left hand direction relative to the section B against the right hand torsional strain so that the teeth suddenly slide out of mesh and allow the upper ends 22 of the slots to suddenly jar against the upper ends of the parts 20. The settling or lowering of the operating string to release the means 11 may be accompanied by a forward rotational strain on the string so that a greater compression strain is required to release the means 11, thus providing for a heavier downward jarring blow.

It is to be particularly noted that the jarring tool provided by the present invention is con-

structed so that fluid cannot be trapped within any of its parts and so that fluid does not in any way retard or interfere with the relative longitudinal movement between the sections 5 A and B or with the setting and releasing of the means 11. The opposite ends of the parts 20 and slots 21 constitute the impact or jarring faces of the tool, and as they are exposed at the outer faces of the tool, circulation fluid cannot be trapped between them and cannot in any way interfere with the free movement of the body sections. The slots 21 are comparatively wide and long so that the interior of the section A is open to the well bore when the section 10 15 A is in its extreme up position relative to the section B, thereby allowing free escape of the fluid within the section A. The tool is particularly simple and inexpensive of manufacture and does not involve any springs, latches, or 20 other parts that are subject to failure or liable to become made inoperative by the presence of solid matter. The toothed means 11 for releasably holding the sections A and B against relative longitudinal movement is fully exposed, and 25 on the outer side of the tool so that its operation is not interfered with by trapped fluid or by accumulations of mud or solid matter.

Having described only a typical form and application of the invention, I do not wish to be 30 restricted to the particular form and application herein set forth, but wish to reserve to myself any variations or modifications that may appear to those skilled in the art or fall within the scope of the following claims.

35 Having described my invention, I claim:
 1. A jarring tool including, a tubular section, a stem section extending into the tubular section, the sections being related for limited relative longitudinal movement, the tubular section 40 having a longitudinal slot in its wall open to its exterior, a lug on the stem section movable in the slot and adapted to cooperate with the ends of the slot to limit relative longitudinal movement of the sections and to provide a jarring 45 action, there being spaced notches in a side of the lug and a wall of the slot forming teeth adapted to cooperate to releasably hold the sections against relative longitudinal movement, the teeth being releasable by a strain on the sections 50 in either direction, and means whereby the teeth of the lug slide past the teeth of the slot upon the release of the teeth.

2. A jarring tool including, a tubular section, a stem section extending into the tubular section, 55 the sections being related for limited relative longitudinal movement, the tubular section having a longitudinal slot in its wall open to its exterior, a lug on the stem section movable in the slot and adapted to cooperate with the ends of the slot to limit relative longitudinal movement of the sections and to provide a jarring action, there 60 being spaced notches in a side of the lug and a wall of the slot forming teeth adapted to cooperate to releasably hold the sections against relative longitudinal movement, the teeth being releasable by a strain on the sections, and means 65 whereby the teeth of the lug slide past the teeth of the slot upon release of the teeth, the said means including parts of the lug at each end of the series of notches in the lug of greater width than the notches in the wall of the slot.

3. A jarring tool including, two relatively movable sections, one section extending into the other, the said other section having a longitudinal 70 slot extending to its exterior to be open to the

well bore, an outwardly projecting part on the first mentioned section operating in the slot and adapted to engage its ends to provide a jarring action between the sections, means conducting circulation fluid through the sections, and means on the said part and said other section for holding the sections against relative longitudinal movement in positions where the said part is spaced between the ends of the slot and releasable by a longitudinal strain on the sections, the last mentioned means including spaced teeth on said part, and spaced teeth on a wall of the slot intermediate the ends of the slot adapted to have releasable meshing engagement with the first named teeth. 15

4. A jarring tool including, a tubular section, a second section extending into the tubular section, the sections being relatively movable, there being a slot in the wall of the tubular section open to the well bore, an outwardly projecting part on the second section operating in the slot and adapted to strike its ends to limit relative movement of the sections and to provide a jarring action, means conducting circulation fluid through the sections, and means for holding the sections against relative movement in positions where the said part is spaced between the ends of the slot and releasable by a longitudinal strain on the sections, the last mentioned means including spaced teeth on said part, and spaced teeth on a wall of the slot intermediate the ends of the slot adapted to have releasable meshing engagement with the first named teeth. 20 25

5. A jarring tool including, a tubular section, a second section extending into the tubular section, the sections being relatively movable, there being a slot in the wall of the tubular section, an outwardly projecting part on the second section operating in the slot and adapted to strike its ends to limit relative movement of the sections 30 and to provide a jarring action, longitudinally spaced teeth on the wall of the slot, and longitudinally spaced teeth on the said part cooperating with the first mentioned teeth to hold the sections against relative movement in positions 35 where the said part is spaced between the ends of the slot, said teeth being releasable by a longitudinal strain on the sections in either direction. 40 45

6. A jarring tool including, two telescoping sections related for relative longitudinal movement, the outer section having a longitudinal slot in its wall extending to its exterior to be open to the well bore, an outwardly projecting part on the inner section movable in the slot and adapted 55 to engage an end of the slot to limit relative movement of the sections and to provide a jarring action, longitudinally spaced projections on the said part and a wall of the open slot adapted to cooperate to hold the sections against relative longitudinal movement, the projections having inclined cooperating surfaces to be releasable by a strain on the sections, the sections having fluid passages, and means for conducting fluid from the passage of one section to the passage of the other section. 60 65

7. A jarring tool including, two telescoping sections related for relative longitudinal movement, the outer section having a longitudinal slot extending through its wall to be open to the well bore, a laterally projecting part on the inner section movable in the slot and adapted to engage its ends to limit relative movement of the sections and to provide a jarring action, a longitudinal series of teeth on the said part, and teeth on a 70 75

wall of the slot spaced between the ends of the slot adapted to cooperate with the first mentioned teeth to hold the sections against relative longitudinal movement in positions where the said 5 part is spaced between the ends of the slot, said teeth being formed to disengage upon a heavy longitudinal strain being put on the sections in either direction.

8. A jarring tool including, two telescoping sections related for relative longitudinal movement, the outer section having a longitudinal slot in its wall open to its external surface to communicate with the well bore, an outwardly projecting part on the inner section movable in the slot and 10 adapted to engage its ends to limit relative movement of the sections and to provide a jarring action, longitudinally spaced teeth on the said part, and teeth on a wall of the slot spaced between the ends of the slot adapted to cooperate with the 15 first mentioned teeth to hold the sections against relative longitudinal movement in positions where the said part is spaced between the ends of the slot, the teeth having tapered upper and lower sides so as to disengage upon a heavy longitudinal 20 strain being put on the sections in either direction.

9. A jarring tool including, a tubular section, a stem section extending into the tubular section, the sections being related for limited relative 25 longitudinal movement, the tubular section having a longitudinal slot in its wall open to its exterior to communicate with the well bore, a lug on the stem section movable in the slot and adapted to cooperate with the ends of the slot to limit 30 relative longitudinal movement of the sections and to provide a jarring action, longitudinally spaced parts on the lug, and a series of longitudinally spaced parts on a wall of the slot adapted 35 to cooperate with the first named parts to hold 40 the sections against relative longitudinal move-

ment, the parts being releasable by a downward force on the sections to bring the lug and an end of the slot into jarring engagement.

10. A jarring tool including, a tubular section, a stem section extending into the tubular section, the sections being related for limited relative longitudinal movement, the tubular section having a longitudinal slot in its wall open to its exterior to communicate with the well bore, a lug on the stem section movable in the slot and 10 adapted to cooperate with the ends of the slot to limit relative longitudinal movement of the sections and to provide a jarring action, there being a recess in a wall of the slot adapted to receive the lug, and longitudinally spaced parts on the 15 lug and the wall of the recess adapted to mesh to releasably hold the sections against relative longitudinal movement, the recess being spaced between the ends of the slot whereby the lug is spaced between the ends of the slot when the 20 said parts are in mesh.

11. A jarring tool to be connected in a tubular string including, two relatively longitudinally movable sections, one section telescoping into the other, one section having a longitudinal slot open 25 at its exterior to communicate with the well bore, a lug on the other section movable in the slot and adapted to engage an end of the slot to provide a jarring action, means for holding the sections against relative longitudinal movement releasable 30 by a longitudinal strain on the sections the said means including longitudinally spaced teeth on the lug and a wall of the slot adapted to mesh to hold the sections against relative movement, 35 the teeth having cooperating inclined sides that cause relative turning between the sections when they disengage, and means for conducting fluid through the sections.

IR A J. McCULLOUGH.
